UNITED STATES PATENT OFFICE

163,542

CUTTING MACHINE FOR MEAT
OR THE LIKE

William C. Schmidt, Hamilton County, Ohio, assignor to The Cincinnati Butchers' Supply Company, Cincinnati, Ohio, a corporation of Ohio

Application December 20, 1949, Serial No. 6,740

Term of patent 14 years

(Cl. D55—1)

To all whom it may concern:

Be it known that I, William C. Schmidt, a citizen of the United States, residing in the county of Hamilton and State of Ohio, have invented a new, original, and ornamental Design for a Cutting Machine for Meat or the like, of which the following is a specification, reference being had to the accompanying drawings, forming part thereof:

Fig. 1 is a side view of a cutting machine for meat or the like showing my new design.

Fig. 2 is a view of the other side of the cutting machine of Fig. 1.

Fig. 3 is a rear view of the cutting machine of Fig. 1.

The dominant features of my design reside in the portions shown in the full lines.

I claim:

The ornamental design for a cutting machine for meat or the like, as shown and described.

WILLIAM C. SCHMIDT.
